I. S. GEMAS

BEARING BRASS FOR TOP ROLLS AND SUPPORT THEREFOR

Filed Jan. 16, 1924

INVENTOR

Ira S. Gemas.
By A. F. Deuel, Jr.
ATTORNEY

UNITED STATES PATENT OFFICE.

IRA S. GEMAS, OF MARTINS FERRY, OHIO.

BEARING BRASS FOR TOP ROLLS AND SUPPORT THEREFOR.

Application filed January 16, 1924. Serial No. 686,530.

To all whom it may concern:

Be it known that I, IRA S. GEMAS, a citizen of the United States of America, and resident of Martins Ferry, county of Belmont, and State of Ohio, have invented certain new and useful Improvements in Bearing Brasses for Top Rolls and Supports Therefor, of which the following is a specification.

10 This invention relates broadly to roll bearings and more specifically to a top bearing for rolling mill rolls.

The primary object of the invention is to provide a readily removable and insertible 15 support or carrier for the top journal brasses of rolling mill rolls.

A further object is to provide a top roll bearing brass support or carrier which permits a limited amount of endwise movement 20 of the brass carried thereby, whereby binding between the inner end of the brass and the fillet of the roll is in large measure prevented.

A still further object is to provide a device 25 of the character mentioned which is insertible in and removable from its place on or in the roll housing from the outer side of the latter, thereby greatly reducing and facilitating the work of mounting new brasses 30 and removing worn brasses as occasion requires.

With these and other objects in view, the invention resides in the features of construction, arrangements of parts and combinations 35 of elements which will hereinafter be fully described, reference being had to the accompanying drawings, in which—

Figure 1 is a longitudinal section of the invention, illustrating its application to the 40 roll and roll housing;

Figure 2 is a bottom plan view of the invention applied, showing the roll removed and the housing in section; and—

Figure 3 is an inner end elevation of the 45 invention, applied.

Referring to said drawings, 1 indicates a roll housing having therein the usual vertical passageway 2 in which the neck 3 of the top roll 4 is received and is vertically movable. Disposed in seated relation to the top 50 of the roll neck 3 is a top roll bearing brass 5 which is rigidly carried on the under side of a metal block 6 of rider type, being preferably of dove-tail form and fitting a correspondingly shaped channel 7 provided 55 therefor in said block. Said block is longi-

tudinally movable on said roll neck 3, being slidably mounted upon a support which comprises horizontal arms or guides 8 rigidly carried by and extending inwardly 60 from a horizontal transverse bar 9 which is adapted to be mounted against the outer face of the housing 1 with its opposite ends received by supporting brackets 10 carried upon the said outer face of the housing at 65 opposite sides of said passageway 2. Said arms or guides 8 are received within channels or mortises 11 provided in the opposite lateral edge portions of the under face of said block, and similar mortises 12 provided 70 in the opposite lateral edge portions of the top face of said block receive therein arms or guides 13 carried by said bar 9 in spaced parallel relation to the arms or guides 8. 75

The block 6 is designed to have a limited 75 range of free movement toward and away from the adjacent fillet 14 of the roll, and, consequently, liability of binding between the brass 5 and said fillet is greatly reduced, if not wholly eliminated, thus to a large extent 80 reducing the liability to roll breakage resulting from excessive friction due to such binding. The extent of such sliding movement in an outward direction may be adjusted by means of an adjusting screw 15 directed inwardly through the bar 9 and adapted to have the adjacent end of the block 6 abut against its point at the outward limit of movement.

The guide members 13 have directed 90 downward therethrough pins or bolts 16 which have their ends received in longitudinal channels 17 provided therefor in the underlying portions of the block 6. Said bolts 16, so received in said channels, while permitting unobstructed sliding movement of the block throughout a predetermined range, cooperate with the inner ends of said channels for preventing chance withdrawal, or displacement, of said block with respect 95 to its supporting frame.

From the foregoing, it will be understood that the top roll bearing brass 5, the rider block 6 and the supporting frame are together, or in assembled relation, introduced 105 in and removed from operative position with respect to the neck of the top roll from the outer side of the roll housing, and that, as a consequence, the work of effecting such introduction and removal is greatly lightened and facilitated.

The brackets 10 have therein longitudinal

slots 18 through which their attaching bolts 19 are directed. When desired, the top brass 5 and rider 6 may be raised and supported in an elevated out-of-the-way position by 5 said brackets, the attaching bolts first being loosened, said brackets then being elevated to any extent allowed by said slots 18, and said bolts finally being retightened for retaining said brackets in their elevated positions.

What is claimed is—

1. A top roll bearing brass and a carrier therefor, comprising a supporting frame embodying a bar adapted to be mounted horizontally against the outer face of a roll housing, parallel guide members carried by and extending inwardly from said bar, a rider-like block carried by and longitudinally slidable on said guide members, 20 and a top brass rigidly carried on the under side of said block.

2. The combination with a roll housing, of a bar adapted for mounting on the outer face of said housing at opposite sides of the 25 passageway in which the roll necks are received, a plurality of parallel guide members carried by said bar and extending horizontally inward through said passageway, a rider-like block slidably carried by 30 said guide members, and a top roll bearing brass carried on the under side of said block.

3. The combination with a roll housing, of a bar adapted for mounting on the outer 35 face of said housing at opposite sides of the passageway in which the roll necks are received, a plurality of parallel guide members carried by said bar and extending horizontally inward through said passageway, 40 a rider-like block slidably carried by said guide members, adjustable means for limiting the extent of outward movement of said block, and a top brass carried on the under

side of said block, and supporting members for said bar mounted upon the housing, 45 said members permitting vertical movement of said bar.

4. The combination with a roll housing having supporting brackets on its outer face at opposite sides of the vertical passageway 50 in which the roll necks are received, of a vertically movable bar having its opposite ends received between said brackets and the housing, a plurality of parallel guide members carried by said bar and extending 55 inward from the latter through said passageway, a rider-like block supported by and longitudinally slidable on said guide members, means for limiting the extent of sliding movement of said block, and a top 60 bearing brass carried on the under face of said block.

5. The combination with a roll housing having supporting brackets on its outer face at opposite sides of the vertical passageway 65 in which the roll necks are received, of a vertically movable bar having its opposite ends received between said brackets and the housing, a plurality of parallel guide members carried by said bar and extending 70 inward from the latter through said passageway, a rider-like block supported by and longitudinally slidable on said guide members, said block having guideways therein 75 in which said guide members are received, means for limiting the extent of sliding movement of said block, and a top roll bearing brass carried on the under face of said block.

In testimony whereof, I affix my signature in presence of two subscribing witnesses.

IRA S. GEMAS.
